(57) **CLAIM**

The ornamental design for a contoured belt clip for folding knife, as shown and described.

DESCRIPTION

FIG. 1 is a perspective view of my new design of a contoured belt clip for a folding knife, the folding knife casing being shown in phantom for purposes of illustration and forming no part of the claimed design;
FIG. 2 is a top plan view thereof as seen through the casing;
FIG. 3 is a bottom plan view thereof;
FIG. 4 is a side elevational view thereof;
FIG. 5 is an opposite side elevational view thereof;
FIG. 6 is a rear elevational view thereof; and,
FIG. 7 is a front elevational view thereof.
